C. T. EVANS

ELECTRIC SWITCH

Filed May 26, 1921

UNITED STATES PATENT OFFICE.

CLARENCE T. EVANS, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

Application filed May 26, 1921. Serial No. 472,642.

To all whom it may concern:

Be it known that I, CLARENCE T. EVANS, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches and more particularly to switches having associated electro-magnetic means controlled thereby to produce a magnetic field for 15 blowout or other purposes.

While not limited thereto the invention is particularly applicable to switches employing such electro-magnetic means for blowout purposes and therefore such application 20 of the invention is selected for specific consideration.

Where switches are employed for interrupting circuits of high potential, as also in certain other instances, it has been found 25 desirable to provide the same with a plurality of sets of contacts connected in parallel and the present invention has among its objects to provide such switches with improved electro-magnetic blowout means.

Another object of the invention is to provide such switches with blowout means so 30 designed as to minimize the amount of conducting material required for the coils thereof or in other words so designed as to obtain a maximum blowout effect by employment 35 of turns of a given cross section.

Another object is to provide blowout means of the aforesaid character which will be effective to the same degree regardless of 40 the sequence in which the plurality of sets of parallel connected contacts disengage.

Another object is to provide a switch of the aforesaid character having blowout means tending to equalize the division of 45 current between its several sets of contacts.

Various other objects and advantages of the invention will hereinafter appear.

The accompanying drawing illustrates 50 a switch embodying the invention in one form which will now be described, it being understood that the same is susceptible of various modifications and of different uses of the magnetic field controlled thereby without departing from the scope of the 55 appended claim.

In the drawing,

Fig. 1 is a front elevational view of the switch;

Fig. 2 is a vertical sectional view through the upper portion of the switch shown in 60 Fig. 1;

Fig. 3 is a top plan view of said switch; and

Fig. 4 is a diagrammatic view illustrating the circuit connections of said switch. 65

Referring to the drawing the switch comprises four movable contacts 1 to 4 carried by the armature member 5 of an electro-magnet 6 best shown in Fig. 2. The contacts 1 to 4 are arranged to respectively engage co-operating stationary contacts 7 to 10 (Fig. 3) said sets of contacts being divided into two parallel connected groups. 70

The contacts 1 and 2 are respectively connected by leads 11 and 12 to a common binding post 13 while their co-operating contacts 7 and 8 are mounted upon and electrically connected to a common supporting member 14 fixed to an insulating base 15 which also carries electro-magnet 6. The 80

contacts 3 and 4 on the other hand are respectively connected by leads 16 and 17 to a common binding post 18 while their co-operating contacts 9 and 10 are mounted upon and electrically connected to a common supporting member 19 also fixed to the support 15 and electrically independent of the supporting member 14. It will thus be apparent that the two sets of co-operating contacts 1-7 and 2-8 provide a conducting path paralleling the sets of contacts 3-9 and 4-10 and that the two sets of contacts of each group likewise parallel one another. Also it will be apparent that even if the two groups of contacts are designed 90

and adjusted to interrupt circuit substantially simultaneously they will be subjected to such inequalities in wear as to render simultaneous disengagement highly improbable and the sequence of disengagement 95

very uncertain. In other words the contacts of either group may disengage prior to disengagement of the contacts of the other group with the result that the contacts of the latter group are subjected to the full current until they disengage and until the arcs drawn therebetween are interrupted. 100

As best illustrated in Fig. 2 each of the contact members 1 to 4 is pivotally mounted on the armature member and biased by a spring 105 110

20 to a given position on said member, said spring being compressed upon engagement of said contact with its respective stationary contact to function in the well-known manner, but of course, it is to be understood that this and other details of construction of the switch are not essential.

The blowout device comprises two coils 21 and 22 and pole pieces 23, 24 and 25, the coil 21 being arranged between pole pieces 23 and 24 and the coil 22 being arranged between pole pieces 24 and 25. The pole pieces 23 and 24 are arranged to receive therebetween the contacts 1-7 and 2-8 and the winding 21 is arranged in series with said contacts. On the other hand the pole pieces 25 and 24 are arranged to receive therebetween the contacts 3-9 and 4-10 and the coil 22 is connected in series with said contacts. The coils 21 and 22 have their adjacent terminals connected to a common binding post 26 while their opposite terminals are respectively connected to the contact supporting members 14 and 19. As illustrated the coils are formed of relatively heavy strips and are respectively provided with tubular core members 27 and 28 threaded by a bolt 29 upon which the pole pieces 23, 24 and 25 are mounted.

30 It will thus be apparent from Fig. 3 that the current traversing the switch divides between the two coils when both groups of contacts of said switch are engaged whereas upon disengagement of the contacts of either group the entire current traverses the coil connected in series with the other group of contacts thereby increasing the magnetic field of the latter coil. Also it will be apparent that the arrangement of pole pieces is such that the magnetic field of either coil when subjected to the full current will be strengthened and concentrated in the region of the contacts connected therewith, thereby providing an effective blowout for the contacts last to disengage. Moreover the reduction in distance between the effective poles of the blowout device affords better control of the arcs to be extinguished, i. e., by providing for strengthening of the effective magnetic lines of force. In this connection it is also to be noted that the blowout coils serve as resistances in the parallel branches of the control circuit and

hence tend to equalize the division of current between the several sets of contacts.

55 Further it will be apparent that this form of blowout device has important structural advantages it being apparent that the coils may be formed of strips of considerably less cross section than would be required assuming use of a single blowout coil subjected continuously to the full current traversing the switch. In fact assuming use of a single coil to produce a magnetic field effective for all of the contacts, said coil 60 would require a number of turns at least equal to the combined turns of windings 21 and 22 and in order to carry the full current continuously, it would require a cross section approximately twice that of the coils 65 shown.

70 The pole pieces 23, 24 and 25 have a pivotal movement about the bolt 29 as an axis whereby they may be moved away from the stationary contacts to give access thereto and preferably said pole pieces are provided with slots 30 whereby they may be readily attached to and removed from the bolt 29. Also the pole pieces are provided with insulating plates providing separate 75 insulating chutes between the pole pieces 23 and 24 and pole pieces 24 and 25. Each chute comprises parallel insulating plates 80 31 and 32 and a transversely extending plate 33 supported by bolts 34 and 35 which pass 85 through all of said plates as well as the pole pieces to provide a unitary structure.

85 What I claim as new and desire to secure by Letters Patent is:

90 The combination with an electric switch having a plurality of sets of cooperating contacts affording parallel conducting paths, of a blow out device comprising a plurality of coils respectively subjected to the current traversing said parallel paths and further comprising end pole pieces to be traversed by the flux of both of said windings 95 when said sets of contacts are closed, and an intermediate pole piece adapted to concentrate the flux of either of said windings 100 in the region of its controlling contacts upon opening of the other of said contacts.

95 In witness whereof, I have hereunto subscribed my name.

CLARENCE T. EVANS.
